UNITED STATES PATENT OFFICE.

ARTHUR LLOYD GIBSON, WILLIAM PARKER GIBSON, AND WILLIAM HENRY ROSS, OF TWICKENHAM, ENGLAND.

ROLLING FIRE-SHUTTER, PARTITION, OR THE LIKE.

1,255,817.

Specification of Letters Patent.

Patented Feb. 5, 1918.

Application filed November 14, 1912, Serial No. 731,253. Renewed June 15, 1917. Serial No. 175,042.

To all whom it may concern:

Be it known that we, ARTHUR LLOYD GIBSON and WILLIAM PARKER GIBSON, both citizens of the United States of America, and WILLIAM HENRY Ross, a subject of His Majesty the King of Great Britain, all residents of Twickenham, England, have invented a certain new and useful Improvement in Rolling Fire-Shutters, Partitions, or the like, of which the following is a specification.

This invention relates to improvements connected with rolling shutters, partitions, or other kinds of heavy roll-up curtains, and particularly to fireproof ones, which are normally held in their rolled-up condition but can when desired be allowed to fall.

In such devices, as heretofore constructed, and especially in those of the larger sizes, the speed of the fall as the curtain approaches the floor becomes so much accelerated by the weight of the part uncoiled that a considerable amount of noise is occasioned by the impact of the curtain on the floor. To some extent the counterbalancing springs act as a brake slightly retarding the fall, and in fact such springs have been for this reason called brakes; but their control was very limited and became relatively less as the speed and weight of the falling curtain acting against them increased.

The invention has for its object to provide means for so retarding the speed of the falling curtain when released that said curtain will reach the ground or limit of its fall without any great noise or undue suddenness.

According to the present invention there is employed a braking or speed controlling or retarding device adapted to exert a progressive or increasing resistance to the fall of the curtain, or set up a resistance at an advance stage in the fall of the curtain; and such braking or speed-controlling device is distinct from the winding-up or retaining spring or springs.

A further advantage, in addition to that of reducing noise and jar, is that the improved apparatus provides for regulating the speed of descent, and thus gives a definite period of time during the fall of the curtain for permitting any persons who may be close at hand to escape from one side to the other.

The invention will now be described more fully with reference to the example thereof shown by way of illustration in the accompanying drawings, in which:—

Figure 1 is a sectional end elevation of a double curtain equipment or outfit embodying the features of the invention.

Fig. 2 is a transverse section thereof taken approximately on the line 2—2 Fig. 1, and

Fig. 3 is an enlarged detail view showing the improved form of braking device indicated in Fig. 1.

The said drawings show a system of apparatus in which the curtains are employed in duplicate or paired, with a space between them. These curtains are indicated at *a a* and are wound on spring drums *b b* which may be constructed and operated in the usual or any suitable way.

The usual operating shaft is shown at *c*, provided with a hand crank *c'*. As heretofore, this shaft is geared with the spring drums *b b*.

The braking or control mechanism is actuated through the intervention of a countershaft *d* which carries at each end a bevel gear wheel *d'* meshing with a bevel gear wheel *e'* on a vertical shaft *e*. This countershaft also carries at each end a pinion *d²* meshing with a smaller pinion *c²* on the shaft *c* by which when raising the curtain the countershaft *d* is driven. On the axle of each of the spring drums *b* is a large spur wheel *b'* gearing with a combined spur and bevel wheel *b²* with which meshes a bevel wheel *e²* on the upper end of the corresponding vertical shaft *e*.

The countershaft *d* constitutes, when the curtain is falling, the operating shaft of the improved control or braking mechanism, which is shown clearly in Fig. 3.

For a suitable portion of its length the shaft *d* is screw threaded at slow pitch as shown at *d³*, and on said screw threaded portion of the shaft is mounted a nut or traveler *f* which is guided along, and prevented from rotating with the shaft by a guide rail *g* with which said nut engages. The other portion of the shaft *d* is plain or non-threaded and carries a sliding collar *h* which is slotted as indicated at *h'* but only at its rear portion, and is likewise guided by the guide rail *g* and serves as the brake member, as hereinafter described. Between the nut *f* and the collar *h* is suspended a dash pot of

which the cylinder or barrel *i* is jointed or otherwise connected to the nut *f* and the piston rod *j* is similarly connected to the collar *h* or conversely. The piston *j'* of this dash 5 pot has a small hole *j''* for permitting liquid contained in the cylinder to escape from one side of the piston to the other. Such hole *j''* is controlled by a ball valve allowing liquid to pass only in one direction. The cylinder 10 is provided with a pipe or by-pass *i'* leading from the forward end to the rear end with which latter it communicates through a small hole *i''*, the size of which latter may be controlled by a needle valve *k*.

15 On the shaft *d* is a fast collar *l* located at such a point on the shaft as not to interfere with the free travel of the loose collar *h* until the determined end of said travel and this portion of the mechanism is inclosed 20 within a box or casing *m* through the ends of which the shaft passes.

The operation of the braking mechanism is as follows:-

The shaft *d* being geared at high speed 25 ratio with the drums *b b*, as soon as the curtain begins to descend said shaft will begin to revolve rapidly, the nut *f* being initially near the extreme end, remote from the fast collar *l*, of the shaft: and, the loose collar *h* being unslotted at its forward part, the forward end of the slot *h'* is closed by a shoulder *h''*, which on the retreat of the collar *h*, abuts against the end face of the guide rail 30 *g*, and locks the collar against further movement along the shaft *d*. As the shaft *d* revolves and the nut *f* consequently travels along its screw-threaded part *d''*, the cylinder *i* of the dash pot will be carried along with it toward the fast collar *l*; and the 35 loose collar *h*, being freely slideable, will be pushed along the shaft by the dash pot, as a whole before the liquid in the latter begins to pass in any appreciable quantity from one side of the piston to the other. There 40 will therefore be little resistance offered to the fall of the curtain, but when the loose collar *h* has come into contact with the fast collar *l* there will be at once a frictional resistance set up between the fixed face of one 45 and the rotating face of the other, and this resistance will increase as the loose collar *h* is pressed more and more forcibly against the fast collar *l*.

It will be noticed that the gearing is so 50 arranged that the ratio between the drum *b* and the brake shaft *d* is for speed; consequently the converse ratio, namely between the brake shaft *d* and the drums *b* is for power, and therefore the brake mechanism

is capable of acting with considerable force. 60 Moreover, owing to the increasing friction between the loose and fast collars *h* and *l*, the braking effect is an increasing one.

In practice, the above described braking mechanism may bring the curtains to a temporary stop before they have reached the bottom of their descent; such stoppage will continue until the liquid remaining within the dash pot has had time to escape from one to the other side of the piston sufficiently to 70 allow such release of the pressure between the loose and fast collars as will permit the descent of the curtains to continue.

The ball valve in the piston allows of the liquid passing freely back upon the raising 75 of the curtain.

The parts of the construction described are susceptible of modification without departing from the gist of the invention as 80 claimed.

What we claim is:

1. In combination with a shutter and a winding means therefor, of means for retarding the descent of the shutter consisting of a threaded shaft operably connected for 85 rotation with said shutter winding means, a rectilinearly movable dash pot and piston therefor, one of said two last named parts operated by the threaded screw and the other having a free movement in a direction 90 parallel to the axis of the threaded screw and means for limiting said movement and therefore retarding the rotation of the threaded shaft.

2. In combination with a shutter and a 95 winding means therefor, of means for retarding the descent of the shutter consisting of a threaded shaft operably connected for rotation with said shutter winding means, a rectilinearly movable dash pot and piston 100 therefor, one of said two last named parts operated by the threaded screw and the other having a braking member and a free movement in a direction parallel to the axis of the threaded screw, means for limiting 105 said movement, and a braking member operated by the shaft co-operating with the braking member carried by the freely movable part to retard the rotation of the shaft.

In testimony whereof we have hereunto 110 set our hands in the presence of two subscribing witnesses.

ARTHUR LLOYD GIBSON.
